UNITED STATES PATENT OFFICE

FRANK L. GORMLEY, OF CHICAGO, ILLINOIS, ASSIGNOR TO THE BUDA COMPANY, OF HARVEY, ILLINOIS, A CORPORATION OF ILLINOIS

LIFTING JACK

Application filed March 17, 1928. Serial No. 262,392.

This invention relates to lifting jacks and particularly to self-lowering jacks and has for its object the production of a jack of this character in which the parts are reduced to a minimum, more simply constructed and more accessible to the operator.

This simplicity of construction being possible as the jack of the present invention is designed to sustain only a weight of thirty-five tons as compared with the weight of fifty tons which the jacks shown and described in my pending application No. 156,111, patented Jan. 8, 1929, as Patent 1,698,053, are designed to sustain.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a plan of a lifting jack embodying the principles of the present invention.

Figure 2 represents an elevation of the same.

Figure 3 represents a section of same on line 3, 3, on Fig. 2, drawn to an enlarged scale.

Figure 4 represents a section of same on line 4, 4, on Fig. 3.

Figure 5 represents a section of same on line 5, 5, on Fig. 4.

Figure 6 represents a section of the clutch mechanism on line 6, 6, on Fig. 3, and

Figure 7 represents a section of the brake mechanism on line 7, 7, on Fig. 3.

Similar characters indicate like parts throughout the several figures of the drawings.

In the drawings, 10 is the base of a lifting jack having a standard or casing 11 extending upwardly therefrom in the upper end of which is a cylindrical bearing for a vertically movable ram 12.

The ram 12 has an enlarged head 13 adapted to rest upon the top of the standard 11 when in its lowest position.

The lower end of the ram 12 has mounted therein a nut 14 threaded to the main lifting screw 15, the lower end of which has keyed thereto a bevel gear 16 meshing with a bevel gear 17 formed upon the actuating shaft 18.

The shaft 18 has mounted on its outer end a device 19 for imparting rotary movement to the shaft 18 in one direction only, and that is, during the lifting operation.

The standard 11 has a lateral extension 20 provided with a bearing for the actuating shaft 18.

Within the chamber formed by the lateral extension 20 is mounted a worm gear 21 secured to the actuating shaft 18 and meshing with a worm 22 formed upon the horizontal shaft 23.

The pitch of the worm 22 is such as to permit it to be rotated by said worm gear 21 in 75 whichever direction the gear 21 may be rotated.

One end of the worm shaft 23 is mounted in a bearing in the wall of extension 20, while the opposite end is mounted in a bearing in 80 the removable cover plate 24.

Roller bearings 25, 26, are provided for the opposite ends of said shaft 23 and these bearings take up all end thrust of worm 85 shaft 23.

Keyed to the shaft 23 is an annular member 27 to which are pivoted a plurality of pawls 28 each provided with a plurality of teeth adapted to engage the ratchet teeth 28a 90

on the ring 29 having a spur gear 30 formed upon the periphery thereof.

The hub 29 α of ring 29 revolves in a bearing 32 formed in a partition 33 within the casing 10 and the ends of the ratchet teeth 28 α contact with the periphery of the pawl carrying member 27.

A plate 34 encloses the pawls 28, this plate being secured to member 27 by screws or 10 studs 35, the screws 35 also forming pivots for the pawls 28.

This plate 34 prevents the displacement of the annular hub 29 α of ring 29 from its bearing 32.

15 The pawls 28 are normally forced outwardly into engagement with the ratchet teeth 28 α on ring 29 by means of the springs 36.

The teeth of gear 30 mesh with the teeth 20 of a pinion 37 formed upon a shaft 38 having bearings in the partition 33 and cover plate 24.

This partition 38 is in a housing 33 α extending laterally from the standard 11 at 25 right angles to the extension 20.

To the shaft 38 is keyed the brake disk 39 having an annular groove 40 in its periphery in which are pivotally mounted a plurality of shoes 41 adapted under centrifugal 30 force to be moved outwardly into contact with the brake arms 42.

The brake arms 42 are pivotally mounted upon a stud 43 extending from the partition 33 of housing 33 α .

35 These arms 42 are provided with overlapping lugs 44 to span the gap between the free ends of said brake arms 42.

The free ends of the arms 42 are parallel and between these ends is a cam member 40 45 formed upon an oscillating shaft 46, one end of which has a bearing in the partition 33 while its opposite end extends through the cover plate 24 and has secured thereto an actuating handle 47.

45 The free ends of the arms 42 are retained in contact with the cam 45 at all times by means of the springs 48, the opposite ends of which are disposed in sockets 48 α formed in the arms 42 and the walls of the casing 11.

50 On the cover plate 24 is an outwardly extending stop lug 49 which limits the movement of the handle 47 when moved to spread apart the arms 42.

55 Each brake shoe 41 has a stud 50 extending therefrom through an opening 51 in the flanges of brake disk 39, said opening having a greater diameter than that of said stud 50.

60 The movement of the shoe 41 about its pivot is limited by said stud 50 coming into contact with the wall of said opening 51.

Owing to this limitation of the outward movement of the shoes 41, the arms 42 may 65 be moved entirely free from contact with

the shoes 41 when it is desired to lower the jack rapidly.

Threaded to the casing 11 is a member 53 having a soft metal head 54 adapted to impinge upon the thread of the worm 22 and prevent any rotation thereof.

This locking of the worm 22 from rotation is effected when it is desired to sustain a load in the same position for a considerable length of time.

This member 53 is provided on its outer end with a winged element 55 by which the member 53 may be rotated to move the soft metal head 54 toward and from the worm 22.

The cover plate 24 is secured to the casing 11 by means of the screws 56.

Ears 57 extend from the opposite sides of the casing 11 and at one side of the center thereof to which are pivoted handles 58 by which the jack may be easily moved.

The ears are disposed as described to better balance the weight of jack when lifted.

A safety locking device 59 is disposed at the upper end of casing 11 which forms no part of the present invention, being fully described in my pending application Ser. No. 156,111, hereinbefore referred to.

By constructing the jack in the manner herein shown and described the parts are reduced to a minimum, a better balanced jack is obtained, and easier access to the various elements is provided.

It is believed that the operation and many advantages of the invention will be understood readily without further description.

Having thus described my invention, I claim:

1. In a self-lowering lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm above said worm gear and meshing therewith, said worm being immovable endwise; a spur gear surrounding one end of the worm shaft having ratchet teeth thereon; a member secured to said shaft and rotatable therewith forming a support for said spur gear; 115 pawls carried by said member coacting with said ratchet teeth; an automatic brake mechanism including a rotatable shaft parallel with said worm adapted to retard the lowering of the ram; and a pinion secured to said shaft and meshing with said spur gear.

2. In a self-lowering lifting jack provided with a steep pitch rotatable screw, a supporting casing therefor, and a vertically movable ram; a bevel gear secured to the lower end 125 of said screw; a driving shaft having a bevel gear meshing with the screw gear; a worm gear on and rotatable with said shaft; a worm above said worm gear and meshing therewith, said worm being immovable end- 130

- wise; a ring surrounding one end of the worm shaft having ratchet teeth formed on its inner wall and spur gear teeth on its periphery, said ratchet teeth and gear teeth being in the same plane; a member secured to said worm shaft and rotatable therewith forming a support for said ring; pawls carried by said member coacting with said ratchet teeth; an automatic brake mechanism including a rotatable shaft parallel with said worm adapted to retard the lowering of the ram; and a pinion secured to said shaft and meshing with said spur gear teeth.
5. In a self-lowering lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm above said worm gear and meshing therewith, said worm being immovable endwise; a ring surrounding one end of said worm shaft having peripheral teeth; a cylindrical member on said worm shaft forming a support for said ring; means carried by said member for rotating said ring in one direction only, said rotating means being in the same plane with said teeth; a pinion 20 meshing with the ring teeth and rotatable thereby; a shaft on which said pinion is mounted; a brake disk on said pinion shaft; and means coacting with said disk for retarding the lowering of said ram.
25. In a self-lowering lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm horizontally disposed above and meshing with said worm gear; a laterally extending housing to said casing having a vertical partition through which the worm shaft extends; a cover plate for said housing having a bearing 30 for the end of said worm shaft; a short shaft parallel to and at the same elevation as said worm rotatable in bearings in said partition and cover plate and having a pinion formed integral therewith; a ring surrounding the worm shaft with a hub rotatable in a cylindrical opening in said partition and having spur gear teeth on its periphery meshing with said pinion; means on said worm shaft for rotating said ring in one direction only; and automatic brake mechanism surrounding said pinion shaft and adapted to retard the lowering of the ram.
35. In a self-lowering lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm above said worm gear and meshing therewith; a ring surrounding one end of the worm shaft provided on its periphery with 40 spur gear teeth and having ratchet teeth thereon in the same plane with the gear teeth; a member secured to said worm shaft and rotatable therewith, with the periphery of which the inner ends of the ratchet teeth contact; a plate secured to said member preventing the displacement of said ring from said member; pawls carried by said member coacting with said ratchet teeth; an automatic brake mechanism including a 45 rotatable shaft parallel with said worm adapted to retard the lowering of the ram; and a pinion secured to said shaft and meshing with said spur gear.
50. In a self-lowering lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm horizontally disposed above and meshing with 55 said worm gear; a laterally extending housing to said casing having a vertical partition through which the worm shaft extends; a cover plate for said housing parallel to said partition and having a bearing for the end of said worm shaft; a short shaft parallel to and at the same elevation as said worm rotatable in bearings in said partition and cover plate and having a pinion formed integral therewith; a ring surrounding the worm shaft and having spur gear teeth on its periphery 60
65. In a self-lowering lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm
